UNITED STATES PATENT OFFICE.

IRWIN B. HOMAN, OF LEBANON, PENNSYLVANIA.

SPRING-CLAMP.

1,134,131.

Specification of Letters Patent.

Patented Apr. 6, 1915.

Application filed January 13, 1915. Serial No. 1,982.

To all whom it may concern:

Be it known that I, IRWIN B. HOMAN, a citizen of the United States, residing at Lebanon, in the county of Lebanon and State 5 of Pennsylvania, have invented certain new and useful Improvements in Spring-Clamps; and I do hereby declare the following to be a full, clear, and exact description of the invention, such as will enable others skilled in 10 the art to which it appertains to make and use the same.

This invention relates to spring clamps for preventing rails, girders and other similar devices, from creeping longitudinally; 15 and it consists in the novel construction of the parts as hereinafter fully described and claimed.

In the drawings, Figure 1 is a cross-section of a railroad rail provided with a 20 spring clamp according to this invention. Fig. 2 is an end view of the spring clamp. Fig. 3 is a plan view of the spring clamp.

The spring clamp is formed of a metallic plate or bar 2 which is adapted to extend 25 crosswise under the bottom flanges 3 of a railroad rail or other rail, girder or bar, which is to be prevented from creeping. The plate or bar 2 has spring lugs 4 at its 30 ends which are hook-shaped in form, and which are adapted to bear on the upper surface of the bottom flanges of the rail. These lugs are bent laterally of the plate or bar 2 in opposite directions, so that they are substantially parallel to each other, and so that 35 they can be slipped upwardly to straddle the base of the rail. The plate or bar is then partially revolved under the rail so that the lugs engage with and clip the rail flanges.

A projection or stop 6 is provided at the 40 middle part of the plate or bar, which extends downwardly and vertically and which is twisted so that it forms an acute angle with the main portion of the plate or bar. When the clamp is forced into close engagement 45 with the base flanges, the projection 6 comes parallel to the cross-tie, or sill, which supports the rail. The clamp is forced or

hammered along the rail until the projection 6 bears against the cross-tie, and thereby prevents the rail from creeping.

50

The lugs spring a little when hammered into engagement with the rail and they grip its base flanges tightly. An inclined lug or tooth 8 is formed at the middle part of the top edge of the plate or bar 2, and this lug 55 has a sharp corner 9 at its top which engages with the bottom of the rail and prevents the spring lugs from slipping.

In the device shown, the bar or plate 2 is partially revolved in the direction of the 60 curved arrow in Fig. 3, to enable the spring lugs to clamp the flanges, but when the spring lugs 4 and the projection 6 are inclined in the reverse direction, the bar or plate is revolved in the opposite direction. 65 The devices can be made either way, right or left hand, as found convenient, in carrying out this invention.

What I claim is:

1. An anti-creeping clamp, comprising a 70 vertical plate having hook-shaped lugs at its ends for engaging the bottom flanges of a rail, said plate having at its middle part, between the said lugs, a vertical stop formed of an extension of the middle part of the 75 plate and arranged at an angle thereto, the top of the stop and the bottom of the main portion of the plate being twisted and inclined downwardly at their junction.

2. An anti-creeping spring clamp, comprising a bar or plate having hook-shaped lugs at its ends which are inclined laterally of it in opposite directions, and having also at its middle part a twisted projection or stop which projects downwardly, said bar 80 or plate having also at the middle part of its upper edge an inclined locking lug or tooth having a sharp corner at its top.

In testimony whereof I have affixed my signature in the presence of two witnesses.

IRWIN B. HOMAN.
